US0D1075474S

(12) **United States Design Patent** (10) **Patent No.:** **US D1,075,474 S**
(45) **Date of Patent:** **** May 20, 2025**

(54) **COMPONENT FOR A LOCK**

(71) Applicant: **GUANGZHOU TUSUNNY HOME PRODUCTS CO., LTD**, Guangzhou (CN)

(72) Inventor: **Hongjuan Wang**, Guangzhou (CN)

(73) Assignee: **GUANGZHOU TUSUNNY HOME PRODUCTS CO., LTD**, Guangzhou (CN)

(**) Term: **15 Years**

(21) Appl. No.: **29/915,629**

(22) Filed: **Nov. 2, 2023**

(30) **Foreign Application Priority Data**

May 5, 2023 (CN) 202330256474.2

(51) **LOC (15) Cl.** **08-07**

(52) **U.S. Cl.**

USPC **D8/343**; D25/48.5

(58) **Field of Classification Search**

USPC D8/14, 330, 331, 339, 341, 343; D25/48.5

(57) **CLAIM**

The ornamental design for a component for a lock, as shown and described.

DESCRIPTION

FIG. 1 is a rear, right and top perspective view of a component for a lock, showing my new design; FIG. 2 is a front, left and bottom perspective view thereof, shown in a used condition;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the component for a lock that form no part of the claimed design.

1 Claim, 8 Drawing Sheets
